OPENABLE COVER FOR AN ELECTRIC CIRCUIT CONTROLLER ENCLOSURE

Harry J. Collins, Jr., Bayside, Wis., assignor to Cutler-Hammer, Inc., Milwaukee, Wis., a corporation of Delaware

Application May 26, 1959, Serial No. 56,083

Term of patent 14 years

(Cl. D26—13)

Fig. 1

Fig. 2

Figure 1 is a perspective view of an openable cover for an electric circuit controller enclosure with the door closed, showing my new design;

Fig. 2 is a sectional view on line 2-2 of Fig. 1;

Fig. 3 is a partial sectional view on line 3-3 of Fig. 1 to an enlarged scale;

Fig. 4 is a perspective as in Fig. 1 with the door open; and

Fig. 5 is a sectional view on line 5-5 of Fig. 4 to an enlarged scale.

The portions shown in broken lines are for illustrative purposes only.

I claim:

The ornamental design for an openable cover for an electric circuit controller enclosure, substantially as shown and described.
